UNITED STATES PATENT OFFICE.

GEORGE STANLEY DONALDSON, OF COBURG, VICTORIA, AUSTRALIA.

LAWN MOWER.

Application filed August 27, 1925, Serial No. 52,861, and in Australia October 11, 1924.

This invention relates to improvements in lawn-mowers of the type having a set of spiral knives, which are driven by gearing from a travelling or supporting wheel and 5 rotate in contact with the rectilinear edge of a stationary knife placed tangentially in relation to said knives.

The principal object of the invention is to provide a lawn-mower, which in addition 10 to its use for ordinary grass-mowing purposes will be found particularly effective in cutting the sward around the edges of lawns, the borders of flower beds and of garden paths.

15 A further object is to provide a lawn-mower having clutch mechanism so arranged and operating that in the retractive or reverse movements of the lawn-mower, the gear drive from the travelling or supporting wheel is not actuated and the knives are not rotated, thus reducing wear and increasing the durability of the machine and its integers.

20 A still further object is to provide improved mountings for the knife-spindle and the trailing roller whereby fine adjustments of these parts can be conveniently made for the purpose of accurately regulating the depth of cut by the knives of the machine.

25 With these and other objects in view, the invention consists of the features of construction, combination and arrangement hereinafter fully described, reference being had to the accompanying drawings, 30 wherein:—

Figure 1 is a view in side elevation of a lawn-mower according to the invention, the cover plate of the near side frame or cheek being removed for clearness of illustration.

40 Figure 2 is a view in plan of the lawn-mower.

Figure 3 is a view in elevation of the near side frame or cheek of the machine.

45 Figure 4 is a plan of Figure 3.

Figure 5 is a view in elevation of the off-side frame or cheek of the machine viewed from the interior.

Figure 6 is a plan of Figure 5.

50 Figure 7 is a sectional elevation of part of one of the travelling or supporting wheels.

Figure 8 is a view in section on line $a-a$ of Figure 7 illustrating the clutch arrangement in a travelling or supporting wheel.

Figure 9 is a detail view illustrating the adjustable mounting of the knife-spindle.

The improved lawn-mower has a near side frame or cheek 2 and an offside frame or cheek 3, both of skeleton formation and constructed of cast-metal. The side frame 2, which has a cover plate 4 detachably bolted thereto, is designed to provide a gear case wherein gear wheels of approved ratios are housed. The frames 2 and 3 are rigidly secured together at required distance apart by transverse tie-bolts 5 passing through apertured bosses 6 formed on the inner surfaces of the side frames or cheeks.

70 A transverse shaft 7 is journaled at its opposite ends in bearing bosses 8 that are formed on and project inwardly from the interior surfaces of the side frames or cheeks 2 and 3, and mounted on said shaft are two travelling or supporting wheels 9. These 75 wheels are positioned between the side frames—see Figure 2—and in order that their distance apart can be conveniently adjusted when occasion requires, collars 10 slideable on the shaft 7 are arranged on opposite 80 sides of said wheels, and are locked in adjusted positions on said shaft by set-screws 11.

85 A spur-wheel 12 is fast on the shaft 7 and meshes with an intermediate spur-wheel 13 revolvable on a short spindle 14, which is secured in a boss 15 formed on the exterior surface of the near side frame or cheek 2. The spur wheel 13 in turn meshes with a pinion 16 formed on the end of a transverse spindle 17. Spider frames 18 are mounted on said spindle 17, and carried by the spider frames are spiral knives 19, which rotate in contact with the rectilinear edge of a stationary knife 20 disposed tangentially thereto.

90 The knives 19 and 20 project on either side beyond the path of the travelling or supporting wheels 9 adjustably mounted between the side frames 2 and 3, and consequently the cutting elements mow the sward beyond the line of said wheels. The lawn-mower can thereby be effectively employed for mowing around the edges of lawns, or the borders of flower beds or garden paths 105 without danger of the travelling wheels coming too close to the edges of lawns or causing injury to flowers or plants.

110 Each of the travelling or supporting wheels 9 has a clutch in its boss 21 whereby

said wheels are automatically locked on the shaft 7 in the propelling movements of the machine and rotary motion is imparted from said shaft through the train of gear wheels 12, 13 and 16 to the knife-spindle 17. Tapering recesses 22 are formed in each of said bosses on opposite sides of its bore eccentrically in relation to the shaft 7, and accommodated in said tapering recesses are 10 friction rollers 23. These rollers jam between the narrow portions of the recesses and the shaft during the forward movements imparted to the lawn-mower, but on the retractive or reverse movements of the 15 machine said friction rollers are caused to enter the wider portions of the recesses within which they now fit loosely, and the wheels 9 are permitted to revolve on said shaft in opposite direction whereby motion is not 20 transmitted to said gear wheels and the spindle carrying the spiral knives. By the arrangement of the clutch mechanism on the shaft 7 carrying the travelling or supporting wheels, the gears are not rotated during 25 the backward or reverse movements of the lawn-mower as is the case in lawn-mowers of general construction wherein the clutch is on the knife-spindle of the machine, and as a result the driving gear is subjected to considerably less wear.

Half-bearings 24 are formed in the side frames or cheeks 2 and 3 and revolvably accommodate the opposite ends of the knife-spindle 17. Bearing caps 25 are fitted 30 around the upper portions of the spindle ends and are secured in position by set-screws 26 fitted in lugs 27 formed on said side frames or cheeks. Adjustment of these set-screws is effected to provide for wear 35 of the half-bearings 24 and the knife-spindle 17.

The stationary knife 20 is detachably fastened to a transverse bar 28, which is secured by screws 29 at its opposite ends to 40 brackets or ledges 30 on the interior surfaces of the side frames 2 and 3. The said trans-

verse bar has at its opposite ends downwardly projecting lugs 31 of semi-circular shape fitting into correspondingly shaped seatings 32, that are formed on the inner surface of 50 said side frames and function as pivotal supports for said bar in the adjustment of the stationary knife 20. By rotating the screws 29, the transverse bar so supported can be given an arcual movement either upwardly or downwardly and thus effect fine 55 adjustments in the position of the stationary knife relatively to the spiral knives 19, when the screws are again tightened to lock the knife-carrying bar in the selected position. 60

A trailing roller 33 is revolvably supported by the lower ends of arms 34 that are secured by bolts 35 passed through elongated slots 36 in the side frames or cheeks 2 and 65 3. The upper ends of the arms 34 are rounded and fit snugly into semi-circular recesses in lugs 37 formed at the rear ends of said side frames or cheeks, thus facilitating 70 the pivotal movement of said arms when the elevation of the trailing roller is being adjusted as provided for by said slots 36.

The lawn-mower handle 38 is fastened to a metal bow frame or yoke 39 having its ends pivoted on bosses 40 that are formed 75 on the inner surfaces of the side frames or cheeks 2 and 3.

What I do claim is:—

A lawn-mower having side frames, a rotating knife mounted in said frames, a transverse bar arranged between the frames, semi-circular lugs on the ends of said bar, semi-circular seatings on the frames to receive the lugs, bolts threaded in a fixture on the frames and in said bar on each side of the 85 lugs thereof, and a stationary knife detachably secured to said bar whereby to permit adjustment of the stationary knife relative to the rotary knife and to secure such stationary knife in adjusted position. 90

In testimony whereof I affix my signature.

GEORGE S. DONALDSON.
